UNITED STATES PATENT OFFICE

2,388,459

BOMB

Charles S. Allen, Jr., Greenville, S. C.

Application November 17, 1942, Serial No. 465,916

1 Claim. (Cl. 102—16)

This invention relates to bombs and more particularly to devices of this nature designed for use in marine warfare to destroy enemy craft of the surface or sub-surface type.

The object of the invention is the provision of a bomb including an improved firing mechanism which is maintained in inoperative condition by hydrostatic pressure of the water as long as it remains submerged but which, when released and brought to or near the water surface, responds to the reduction in the hydrostatic pressure and automatically explodes.

A further object of the invention is the provision of an automatic bomb and anchoring or mooring means associated therewith, whereby one or a plurality of the bombs may be maintained in submerged positions in sea lanes most likely to be traversed by enemy craft.

In the accompanying drawing wherein an improved embodiment of the invention is illustrated:

Figure 1 is a perspective view of the improved bomb applied to use, showing several of such devices attached to a buoyant net.

Figure 2 is an enlarged sectional view of the upper portion of the bomb casing illustrating the internal mechanism thereof.

Figure 3 is a side elevation of the complete bomb.

Referring to the drawing in detail, the numerals 10 and 11 indicate two parts of a bomb casing which are flanged at their meeting edges as indicated at 12 and secured together. The lower part 10 is designed to accommodate an explosive charge 13 and a partition 14 is secured between the flanges 12 and divides the interior of the casing into two chambers, one of which accommodates the explosive charge 13 and the other, which is enclosed by the casing part 11, forms a housing for the firing mechanism.

The dome-shaped upper part 11 of the casing is formed with an aperture through which is introduced a pipe 15 rigidly secured in position by nuts 16 threaded on the end thereof and engaging the inner and outer surfaces of the part 11. The inner extremity of the pipe 15 is provided with a head 17 which supports the pressure responsive element 18 which, under normal atmospheric pressure, is curved from end to end. The pressure sensitive element 18 is hollow and communicates with the interior of the pipe 15 by a bore 19 formed in the head 17, whereby the pressure sensitive element 18 is internally subjected to the pressure of the water in which the automatic bomb is submerged.

A pair of contact members 20 and 21 are arranged in the upper chamber of the casing and are disposed on opposite sides of the free end of the pressure sensitive element 18 when the latter is in the condition it occupies when subjected to atmospheric pressure. The contact member 21 is fixed while the contact member 20 is slidable and guided by a pin 22 engaging in a slot 23 formed longitudinally thereof. Initially the slidable contact member 20 is spaced a substantial distance from the stationary contact member 21 and it is held in this position by the tension of a spring 24.

The edge of the slidable contact member 20 adjacent the free end of the pressure sensitive element 18 is formed with a recess 24 in which the reduced terminal of the element 18 is engaged when subjected to a predetermined degree of hydrostatic pressure as, for instance, when the automatic bomb is submerged to a predetermined depth.

The upper chamber of the bomb casing also encloses an electric battery 25 or other suitable source of electric energy, one pole of which is connected by a conductor 26 with the stationary contact member 21 and the opposite pole thereof is connected by a conductor 27 with one terminal of a fuse or other igniting device 28. The opposite terminal of the igniting device is connected by a conductor 29 with the contact member 20 and thus when the two contact members 20 and 21 are mutually engaged the circuit of the fuse 28 is completed and the spark or heat thus generated ignites the explosive charge 13 in the lower part of the casing thus producing a violent explosion at or near the surface of the water, depending upon the sensibility of the element 18 to the variations in pressure to which it is subjected.

As illustrated in Figure 2 the free end of the flexible pressure responsive element 18 is normally disposed in the space between the contact members 20 and 21 so that during a fairly wide range of pressures to which the element 18 is subjected it will not cause premature or unintentional explosion of the bomb. However, when the casing is submerged to a substantial predetermined depth below the surface of the water, the pressure of the latter acts to straighten the flexible element 18 and in so doing the free end thereof engages the underside of the slidable contact member 20 and comes to rest in the recess 24. Thus an operative connection between the flexible pressure responsive element 18 and the contact member 20 is established, and

when the bomb is raised to or adjacent the surface of the water, the flexible element 18 responding to the decrease in hydrostatic pressure tends to resume its curved condition and in so doing moves the slidable contact member 20 into engagement with the stationary contact member 21 thereby completing the circuit of the igniting fuse 28 and causing the ignition and explosion of the charge 13.

Various arrangements may be adopted for anchoring the one or more of the automatic bombs in position below the surface of the water, but this is preferably accomplished by means of a net in which the surface or sub-surface craft becomes entangled during passage. The net is preferably composed of vertical and horizontal strands 20 attached at the lower end to an appropriate number of anchoring cables 31 and attached to anchors 32 which normally rest on the bottom of the body of water. The net 30 is maintained in an upright operative position by buoyant bodies 33 attached to the upper strand and preferably formed of frangible, transparent material so as to render them practically invisible. The anchoring cables 31 are of substantially less tensile strength than the strands of the net 30 so that when a vessel engaging the net severs the anchoring cables 31 permitting the net, together with the bombs, to rise to the sur-

face of the water under the influence of the buoyant bodies 33. By varying the responsiveness of the flexible element 18 to the internal pressure exerted thereon the automatic bomb may be caused to explode either at the surface of the water or at variable points below the surface, as will be understood.

What I claim is:

A bomb comprising a casing, a charge firing means in said casing including normally spaced stationary and movable contact members, a catch shoulder and an inclined surface on the movable contact member, a deformable pressure controlled element, means for subjecting said element to the pressure of the medium surrounding said casing, said element having one end inoperatively disposed in the space between said members when subjected to atmospheric pressure, said end moving along said inclined surface and beyond said shoulder when said element is subjected to hydrostatic pressure of a predetermined value, and means for displacing the movable member to engage said shoulder over said end of the element whereby the contact members are moved into engagement by subsequent deformation of the element in response to a reduction in the hydrostatic pressure.
